UNITED STATES PATENT OFFICE.

ALFRED H. BARTSCH, OF SPRINGFIELD, MASSACHUSETTS, ASSIGNOR TO AMERICAN BOSCH MAGNETO CORPORATION, OF SPRINGFIELD, MASSACHUSETTS, A CORPORATION OF NEW YORK.

DESIGN FOR AN ARMATURE OF A MAGNETO-ELECTRIC MACHINE.

54,827.

Specification for Design.

Patented Apr. 13, 1920.

Application filed September 26, 1919. Serial No. 326,694. Term of patent 14 years.

To all whom it may concern:

Be it known that I, ALFRED H. BARTSCH, a citizen of the United States, residing at 39 Forest Park avenue, Springfield, county of Hampden, State of Massachusetts, have invented a new, original, and ornamental Design for an Armature of a Magneto-Electric Machine, of which the following is a specification, reference being had to the accompanying drawing, forming part thereof.

The figure is a perspective view of an armature of a magneto electric machine, showing my ornamental design for a tape binder therefor.

I claim:

The ornamental design for an armature of a magneto electric machine.

ALFRED H. BARTSCH.
